UNITED STATES PATENT OFFICE.

JOHN LEEPER HENRY, OF WATSONVILLE, CALIFORNIA.

WATER-BICYCLE.

No. 883,018.

Specification of Letters Patent. Patented March 24, 1908.

Application filed July 25, 1907. Serial No. 385,464.

To all whom it may concern:

Be it known that I, JOHN LEEPER HENRY, a citizen of the United States, and a resident of Watsonville, in the county of Santa Cruz and State of California, have invented a new and improved Water-Bicycle, of which the following is a full, clear, and exact description.

The object of this invention is to provide novel details of construction for a bicycle, which adapt it for easy and rapid propulsion upon and over the surface of a body of water, and also enable the device to be guided in any desired direction.

The invention consists in the novel construction and combination of parts, as is hereinafter described and defined in the appended claims.

Reference is to be had to the accompanying drawings forming a part of this specification, in which similar characters of reference indicate corresponding parts in all the figures.

Figure 1 is a side view of a device embodying my invention; Fig. 2 is a front elevation of the same; Fig. 3 is a plan view of the improvement, and Fig. 4 is an enlarged transverse sectional view of details, substantially on the line 4—4 in Fig. 1.

The frame of the device that supports a rider is as at present constructed in the form similar to that employed for a popular style of land bicycles, and briefly described consists of a forward tubular post 5, a saddle supporting post 6, inclined rearward similarly to the inclination given the forward post, a rear frame post 7, a top brace 8, that extends between the front post 5 and the saddle post 6, and a lower brace 9, which connects the posts 5 and 6 with a horizontal transverse box 10, wherein a pedal shaft 10^a is journaled, said shaft at its ends carrying pedal arms and pedals, as represented at 10^b in Figs. 1 and 3. The tubular front frame post 5, at its lower end merges into a four-limbed fork, said limbs a, b, c, d, being mounted upon two tubular boxes 5^a which are axially aligned and receive two axles or shafts 5^b. The rear post 7 of the frame is forked, providing two depending limbs 7^a that are affixed upon a horizontal tubular box 7^b, wherin a shaft or axle 7^c is placed and adapted for rotation, and a brace 7^d extends between the boxes 10 and 7^b. Upon the two forward shafts 5^b, two similar drums 8 are mounted and secured, a sufficient space being allowed between said drums to accommodate the fork members of the front frame post 5. On the

end portions of the rear shaft 7^c, two drums 9, similar to the drums 8, are mounted and secured and, as shown in Fig. 1, the drums are preferably given polygonal form, having any number of sides that will best adapt them for service.

Upon the drums 8 and 9, that are disposed oppositely at each side of the machine, two similar endless, buoyant propeller bands are respectively mounted at their looped ends. Each propeller band consists of a suitable number of hermetically sealed floats 10^c, preferably in rectangular box form, having similar dimensions, that should be so proportioned as to permit the innermost sides of the floats to seat upon respective sides of the polygonal peripheries of the drums 8 and 9. The box-like floats 10^c are connected together flexibly in sequence, either by mounting them upon an endless band or preferably by hinging together their adjacent inner edges, as shown at a' in Fig. 3. The propeller bands are rendered taut so as to operate effectively, and upon each band, at suitable intervals, a series of radial blades 11 are secured, which are disposed on the outer surfaces of the bands for engagement with the water when the machine is operated.

In the front frame post 5, a steering rod 5^d is positioned, having a handle bar 5^e of usual form secured transversely upon the upper end thereof, and upon the lower end of said rod, a rudder blade 5^f is carried that by manipulation of the handle bar, gives direction to the floating machine when the latter is propelled. There is a saddle 6^a mounted upon the post 6, whereon the operator of the machine may be seated, so that he may operate the pedals and control the direction of the machine by manipulation of the handle bar 5^e. Upon the pedal shaft 10^a, a sprocket gear b' is secured, and a similar gear c' is affixed upon the rear axle 7^c opposite the gear b', these gears being connected with a chain d'.

The operation of the machine is extremely simple and reliable, it being understood that the device in complete condition is placed in a body of water having sufficient depth to float the structure and the operator thereon. The blades 11 on the lower runs of the endless propeller bands that are resting in the water, will forcibly press against the latter when the operator rotates the rear axle 7^c and drums 9, which will cause the longitudinal movement of the upper and lower runs of

the endless propeller bands in opposite directions, the lower run moving in direction of the arrow x in Fig. 1, which will propel the machine in a forward direction, or laterally if the rudder is turned to effect such a change in direction. It is evident that by pedaling in a well-known manner, the direction of the machine may be reversed or run backward, so that perfect control of its movement is afforded.

While I have shown the invention as applied upon a bicycle to be driven by the applied power of the operator, I wish it understood that I may use other power for operation of the device, such as a motor bicycle of any available form.

Having thus described my invention, I claim as new and desire to secure by Letters Patent:

2. A device of the class described, comprising a frame, spaced axles journaled on the frame, a hollow water-tight drum having a polygonal contour secured on the ends of each axle, endless bands formed of a series of water-tight rectangular boxes hinged together at adjacent corners, running on the drums, the boxes composing the bands being

of substantially the same area as the polygonal surfaces of the drums whereby to contact therewith as the drums are rotated, and means for rotating the drums.

2. The combination with a frame, spaced axles rotatable on the frame, and means for rotating one axle by foot power, of two hollow water-tight drums secured on respective ends of each axle, said drums having polygonal contours, two endless bands, each band formed of a series of water-tight rectangular boxes hinged together at adjacent corners, the bands having looped ends, boxes composing the loops having contact throughout their areas with respective sides on the peripheries of the drums whereon said bands are mounted, means for rotating the drums by applied foot power, and blades radiating from the drums at intervals.

In testimony whereof I have signed my name to this specification in the presence of two subscribing witnesses.

JOHN BEEPER HENRY
